UNITED STATES PATENT OFFICE.

LESLIE R. N. CARVALHO, OF TOLEDO, OHIO, ASSIGNOR TO THE CLOSURE SERVICE COMPANY, OF TOLEDO, OHIO, A CORPORATION OF OHIO.

CAP FOR BOTTLES OR OTHER CONTAINERS.

Application filed June 8, 1924. Serial No. 718,757.

My invention relates to a cap adapted to form a closure for a bottle or other container. More particularly, it relates to a cap formed of a single piece of resilient sheet metal drawn to shape and adapted to be snapped into position on the container.

An object of the present invention is to provide an improved form of cap having greater resiliency and a wider range of elasticity than caps of this type heretofore in use.

Other objects of the invention will appear hereinafter.

In the accompanying drawings:

15 Figure 1 is a top plan view of a cap constructed in accordance with my invention.

Figure 2 is a side elevation of the cap.

Figure 3 is a sectional elevation of the same.

20 Figure 4 shows a bottle with a cap in position thereon.

Figure 5 is a bottom plan view of the cap.

The construction herein set forth embodies certain features disclosed in my co-pending 25 application, Serial Number 694,514, filed February 23, 1924.

The cap is preferably stamped out of flat sheet metal and drawn to its finished shape. It comprises a concave circular top portion 30 10, the periphery 11 of which is curved downward to provide a flange portion which fits over the lip of a bottle 9. The flange of the cap has kerfs or cut-away portions 12 at regular intervals around the cap, thereby 35 providing an annular series of spring tongues or tabs 13 which are curved inward to engage beneath the lip of the bottle. The lower ends or tips of said tongues are curved outwardly to assist in placing the cap on the 40 bottle and to increase the strength and resiliency of the tongues. One of the tongues is extended to form a finger piece 14. A liner 17 of cork or other suitable material is placed within the cap.

45 By reference to Figures 1 and 5, it will be observed that the outline or periphery of the cap is not a true circle, but approximates a polygon, being approximately hexagonal shape in the particular form of cap shown.

50 That is to say, the tabs 13 as seen in plan view are somewhat flattened or have longer

radii of curvature than the radius of the cap. Also, the outline of the cap at the bases 15 of the kerfs 12 comprises comparatively abrupt curves uniting the curves 16 which form the bases of the tabs 13, said curves 16 having a substantially longer radius of curvature than the radius of the cap.

As a result of this widening of the curvature of the tabs 13, they are considerably more resilient than when curved concentrically with the cap and can also be sprung outwardly to a greater extent without liability of tearing the metal at the upper ends of the kerfs or otherwise injuring or permanently distorting the cap. Also, with this construction, a more certain and reliable sealing of the bottle can be obtained and the cap will more readily accommodate itself to variations in the size and shape of the lip of the bottle to which it is applied.

Modifications may be resorted to within the spirit and scope of my invention.

What I claim is:

1. A bottle cap consisting of a single piece 15 of resilient sheet metal comprising a top portion and an annular flange portion, said flange portion comprising an annular series of spring holding tabs or tongues each curved about an axis parallel with the main axis of 80 the cap, and each having a greater radius of curvature than the radius of the cap.

2. A cap consisting of a single piece of sheet metal comprising a circular convex top portion and a flange portion, the peripheral portion of the cap which unites the top and flange portions being in the form of a wide curve, said flange portion comprising an annular series of spring holding tabs separated by kerfs which extend upwardly into said 85 peripheral portion of the cap, said peripheral portion being approximately polygonal in outline, the sides of the polygon forming the bases of said tabs and each having its radius of curvature of greater length than 90 the radius of the cap, said sides merging into each other at the bases of the kerfs.

Signed at Toledo, in the county of Lucas and State of Ohio, this 6th day of June, 1924.

LESLIE R. N. CARVALHO.
